UNITED STATES PATENT OFFICE.

JAMES H. EGAN, OF PHILADELPHIA, PENNSYLVANIA.

DESIGN FOR A VENDING-MACHINE.

55,848.

Specification for Design.

Patented July 20, 1920.

Application filed November 8, 1919. Serial No. 336,747. Term of patent 7 years.

To all whom it may concern:

Be it known that I, JAMES H. EGAN, a citizen of the United States, residing at Philadelphia, in the county of Philadelphia and State of Pennsylvania, have invented a new, original, and ornamental Design for Vending-Machines, of which the following is a specification, reference being had to the accompanying drawing, forming part thereof.

Figure 1 is a side elevation and Fig. 2 is a front elevation of a vending machine, showing my new design.

I claim:

The ornamental design for a vending machine as shown.

JAMES H. EGAN.
